UNITED STATES PATENT OFFICE.

EDGAR M. STROUD, OF JENKINTOWN, PENNSYLVANIA.

GOLF-SCORE DEVICE.

1,193,441.

Specification of Letters Patent.

Patented Aug. 1, 1916.

Application filed September 13, 1915. Serial No. 50,490.

To all whom it may concern:

Be it known that I, EDGAR M. STROUD, a citizen of the United States, residing at Jenkintown, in the county of Montgomery and State of Pennsylvania, have invented a certain new and useful Improved Golf-Score Device, of which the following is a specification.

This invention, generally speaking, relates to score cards, but has more particular relation to a device calculated for use by golfers in keeping an accurate record of strokes taken in negotiating the various holes of a golf links.

15 The principal objects of the present invention reside in the providing of a device of this character so shaped and proportioned that it may be readily carried upon the person; in the providing of a comparatively inexpensive, strong, durable and efficient scoring device; and in the providing of a device which may be readily used as an advertising medium.

20 Other and further objects of the invention reside in the providing of certain new and novel arrangements and combinations of parts as will hereinafter more fully appear.

The invention consists of the improvements hereinafter described and finally 25 claimed.

The nature, characteristic features and scope of the invention will be more fully understood from the following description taken in connection with the accompanying 30 drawing forming part hereof and in which:

Figure 1, is a view in elevation illustrating one face of the scoring device. Fig. 2, is a similar view of the opposite face, a portion thereof being broken away to illustrate a detail of construction. Fig. 3, is an edge view of the scoring device, and Fig. 4, is a similar view of the various parts about to be assembled.

In the drawings, there is disclosed a physical embodiment of the invention, the same being designed in a manner best known to me at this time for practising the invention. Obviously details of construction may be varied without departing from the fair 45 spirit and scope of the appended claims.

In the specific form of device disclosed in the drawings, the same is shown as embracing a thin, flat, rectangular structure calculated to be readily carried in the pocket 50 of golfers' wearing apparel, as is customary with score cards now in vogue. Such struc-

ture, generally stated, comprises a backing element, two face plates, including complementary small scoring-disks, and a pair of large disks or dials registering total strokes 60 taken. The backing element, which is preferably made of relatively thick card-board or the like, is designated *a*, and is of rectangular shape. Fixed to each face of such backing element, as by eyelets *b*, or equivalent securing mediums is a very thin, rectangular card, preferably of celluloid on account of its adaptability for the purposes intended. These cards are designated *c*, and *d*, the corners being slightly rounded as at *e*. 70 Marginally considered, each card extends a considerable distance beyond the backing element *a*, and is notched as shown, the notches of the respective cards, however, not being disposed in register with one another. The inner face of each card, opposite each notched portion, is provided with a small rotatable scoring disk *f*, preferably of celluloid, and so disposed that a portion of such disk is discernible through a notched 80 portion of a card. The exposed portions of the peripheral edges of such disks, which are serrated as at *g*, for ready turning, however, are so disposed that they lie inside of the marginal contour of the cards, see Figs. 85 1 and 2. This is so that when the device is being inserted within or removed from a golfer's pocket, the disks of either set be not accidentally displaced. The disks *f*, are 90 rotatably secured to place by means of eyelets *n*, or equivalent mediums. Each disk upon its outer face has delineated thereon in the form of a circle numerals ranging from naught upward as high as desired, whereby in rotating a disk, said numerals 95 may register with the U-shaped portion *h*, of the notches before described. The portion *h*, of such notches is extended in a generally flaring portion *i*, for finger tip accommodation so that the disks may be readily 100 rotated. Thus positioned, each disk, in rotation, frictionally bears between a card *c*, or *d*, and the backing element *a*, see Fig. 2, the backing element serving to space apart the two series of disks, however. Further as the two sets of disks have staggered 105 relation one with another the disks of one set may be operated without accidental turning of the disks of the other set. A regulation golf course consists of eighteen holes, of 110 which the negotiation of the first nine is termed "out" and the negotiation of the

remaining nine holes as "in." The card *c*, for illustrative purposes has delineated thereon the words "Out" and "Holes," and adjacent each disk *f*, there is delineated a 5 numeral, which numerals range consecutively from 1, to 9. The remaining small disk, which is designated *f'*, is for registering the number of points "up" or "down" of the player during the first nine holes. The 10 card *d*, has delineated thereon the words "In," "Holes," "Up"—"Down" and the disks *f*, have arranged adjacent thereto consecutively numerals ranging from 10, to 18. The disk *f'*, is a companion disk to the 15 disk *f'*.

Rotatably secured to the outer face of each card *c—d*, is a relatively large disk or dial *j*, an eyelet *k*, being employed for the purpose. Each disk *j*, is marginally provided 20 with graduations ranging from say twenty upward as may be desired. These disks or dials *j*, are used for computing the total number of strokes taken, as registered by the smaller disks, some suitable designation 25 mark as *m*, being present upon each card *c—d*, to indicate the point with which the desired graduation shall register.

In a round of golf, the above described device is used as follows:—The player upon 30 "holing out" at #1 green moves the small disk corresponding to "hole 1" upon the "out" side of the scoring device so as to register the number of strokes taken. This operation is repeated again and again hole 35 by hole until the first nine holes are played, which in golf parlance, is termed "the turn." The total number of strokes taken are then computed and registered by means of the larger dial or disk. Such score is known as 40 "medal score." If the player be engaged in "match play," he or she is also either "up or down at the turn" and such record may be registered by disk *f'*. A record of the "in" or homeward journey is kept in the 45 same manner so that when the player reaches the club-house, an accurate record may be "turned in" of the complete round. As at present practised, a player provides himself or herself with a score-card upon which the 50 score is kept by means of a pencil. It is frequently left to a "caddie" to keep the score for a number of persons, which procedure has its disadvantages as will be readily understood. Further, pencils are 55 frequently forgotten or lost and a "caddie" has to be sent back to the club-house to procure another. These and other disadvantages are successfully eliminated by the use 60 of a scoring device as above described. The device may be made very cheaply and ample space is present thereon upon which adver-

tising matter may be placed, if desired, the advantages of which will readily be appreciated.

What I claim is:

65

1. A device of the class described embracing a backing element, a face-plate rigidly secured to each face of said backing element, and a set of rotatably mounted scoring disks for each face plate so positioned that the two sets of scoring disks have staggered relation and that the peripheral edges thereof do not protrude beyond the marginal contour of a face-plate. 70

2. A device of the class described embracing a backing element, a face-plate rigidly secured to each face of said backing element, the marginal edges of each face-plate being notched at intervals for finger tip accommodation, the two sets of notches having staggered relation, and a set of rotatably mounted scoring disks for each face-plate and so positioned that a notch is in register with each disk, the peripheral edges of which disks do not protrude beyond the contour 75 of a face-plate. 80

3. A device of the class described embracing a backing element, a face-plate rigidly secured to each face of said backing element, each face-plate being shaped and proportioned to marginally extend beyond the backing element an appreciable distance, the marginal edges of each face-plate being notched at intervals for finger tip accommodation, whereof the notches of one face-plate are in staggered relation with respect 90 to the notches of the other face-plate, and a set of rotatably mounted scoring disks for each face-plate, so positioned that a notch 95 is in register with each disk, the peripheral edges of which disks do not protrude beyond the marginal contour of the face-plate. 100

4. A device of the class described embracing a backing element, a face-plate rigidly secured to each face thereof, the marginal edges of which are notched at intervals to form combined finger tip accommodating and sight openings, the two sets of notches having staggered relation and a series of relatively small scoring disks rotatably 105 mounted between said backing element and each face-plate and so positioned that a notch is in register with each disk, the peripheral edges of which disks do not protrude beyond the contour of the face-plate. 110 115

In testimony whereof, I have hereunto signed my name.

EDGAR M. STROUD.
